UNITED STATES PATENT OFFICE.

WILLIAM I. WHEELER, OF SCOTTVILLE, ILLINOIS.

POWER-TRANSMISSION MECHANISM.

1,422,507.

Specification of Letters Patent. Patented July 11, 1922.

Application filed November 20, 1920, Serial No. 425,463. Renewed January 7, 1922. Serial No. 527,762.

To all whom it may concern:

Be it known that I, WILLIAM I. WHEELER, a citizen of the United States, residing at Scottville, in the county of Macoupin and State of Illinois, have invented certain new and useful Improvements in Power-Transmission Mechanisms, of which the following is a specification, reference being had to the accompanying drawings.

10 This invention relates to power transmission mechanisms and has relation more particularly to a mechanism of the type disclosed in my pending applications, Serial No. 401,892 and Serial No. 401,893, filed August 15, 1920, and Serial No. 410,449, filed September 15, 1920, and it is an object of the invention to provide a mechanism of this general character wherein the centrifugal or automatically operating clutching means has 20 coacting therewith novel and improved mechanism for rendering said means active or inactive as the occasions of practice may require.

Another object of the invention is to provide novel and improved means whereby the automatic operating mechanism for the clutching means may be rendered inactive to prevent undue wear on said clutching means and particularly when it is desired to 30 run at any fixed speed for a definite time as may be occasioned in running in several miles of mud or sand or on long grades and similar road conditions.

The invention consists in the details of 35 construction and in the combination and arrangement of the several parts of my improved power transmission mechanism whereby certain important advantages are attained and the device rendered simpler, 40 less expensive and otherwise more convenient and advantageous for use, as will be hereinafter more fully set forth.

The novel features of my invention will hereinafter be definitely claimed.

45 In order that my invention may be the better understood, I will now proceed to describe the same with reference to the accompanying drawings, wherein:

Figure 1 is a view partly in longitudinal section and partly in side elevation of a transmission mechanism constructed in accordance with an embodiment of my invention.

50 Figure 2 is a sectional view on a reduced scale taken on the line 2-2 of Figure 1.

Figure 3 is a sectional view on a reduced scale taken substantially on the line 3-3 of Figure 1.

Figure 4 is a sectional view on a reduced scale taken substantially on the line 4-4 of Figure 1, and

Figure 5 is a view in side elevation of one of the stop members as herein embodied.

My improved device as herein disclosed is shown used in connection with a power transmission mechanism of a type set forth in my pending application, Serial No. 401,893, filed August 7, 1920, although it is to be understood that it can be employed with equal facility in connection with the structure shown in my other two pending applications above referred to or in connection with any transmission mechanism wherein the clutching means is automatically controlled by a weighted arm or its equivalent.

As disclosed in the accompanying drawings, D denotes the driving shaft of a motor supported in a conventional manner and which has loosely mounted thereon a plate 4 constituting an end or head of the housing H. Coacting with the plate 4 is a clutch mechanism substantially the same as a similar structure embodied in my pending applications hereinbefore referred to and as claimed in my further pending application, Serial No. 293,200, filed April 28, 1919.

The end or head 12 of the housing H remote from the plate 4 is freely mounted on the driven shaft S so that the shafts D and S and the housing H are capable of independent rotation or for rotation in unison.

The inserted end extremity of the shaft D has fixed thereto a relatively broad gear 15. Meshing with the gear 15 are the diametrically opposed gears 16. Each of the gears 16 is fixed to a shaft 17 rotatably supported by a carriage 18. The carriage 18 is supported by the wall of the housing or casing H for sliding movement in a direction longitudinal of the shafts D and S.

The inserted end extremity of the shaft S has affixed thereto a gear 19 preferably of a greater radius than the gear 15. The gear 19 is in mesh with the gears 20, when the carriages are in one position, said gears 20 being each fixed to a shaft 17. By this means, the driving shaft D is operatively engaged with the driven shaft S and in a manner whereby the driven shaft S may be rotated at a speed less than the speed of the

driving shaft D. The various gears just referred to may be of any desired ratios so that the ratio of speed between the driving shaft D and the driven shaft S may be as 5 preferred.

Each of the carriages 18 is also provided with a relatively broad gear 21 constantly in mesh with a gear 16. When the carriages 18 are sufficiently moved in a direction inwardly of the shaft S, the gears 20 disengage from the gear 19 and the gears 21 are brought into mesh with the gear 19, resulting in a reverse rotation of the shaft S. When this reversing of the direction of rotation of the shaft S is required, a suitable clutching means generally indicated at 22 is employed to positively hold the housing or casing H against rotation. The mechanism as generally indicated at 22 may be of any 10 type preferred and is adapted to be manually operated from a point exteriorly of the housing or casing A and may be of the construction indicated in my pending application, Serial No. 401,892, filed August 7, 1920.

25 23 denotes an actuating mechanism for the carriages 18 and which mechanism may be operated in any desired manner. I wish it to be understood that it is not my purpose to limit the present embodiment of my invention to this particular arrangement of gears or reversing mechanism just described as any conventional mechanism may be substituted therefor.

Keyed or otherwise secured to the driven shaft at a point inwardly of the housing or casing H and in close proximity thereto is a disc or plate 24. The disc or plate 24 at diametrically opposed points is provided with the inwardly directed arms 25 of a 30 length to extend inwardly of the housing or casing H along the major length thereof. The arms 25 are relatively broad and operatively engaged with said arms 25 at a plurality of points spaced longitudinally thereof. 35 are the clutching units C. Each of said units C is adapted for coaction with the housing or casing H, each of said clutching units in itself being of a tension insufficient to positively lock or hold the housing or casing 40 H against rotary movement relative thereto but the combined action of said clutching units being sufficient to effect such action.

Each of the clutching units C comprises the band or brake sections 26, an end portion 55 of one of said sections 26 being pivotally engaged, as at 27, with an arm 25 at one side of its transverse center, while an end portion of the second band or brake section is pivotally engaged, as at 28, with a second arm 25 at the opposite side of its transverse center. The opposite or free end portion of each of the brake or band sections 26 is provided with an ear or extension 29 extending through a transversely disposed slot 30 formed in the adjacent arm 25.

Each of the arms 25 outwardly of the extensions or ears 29 is provided with a rock shaft 31 extending longitudinally of the arms 25 and rotatably supported by the bearings 32. Fixed to the shaft 31 are the cam members 33 of a number equal to the number of the extensions or ears 29 and each of said cam members 33 has separate coaction with a single one of said ears or extensions 29.

An end portion of each of the shafts 31 is 75 provided with the laterally disposed arm 34 provided at its free end portion with a weighted member 35 so that under the centrifugal force created by the rotation of the disc or plate 24 with the shaft S, the arms 34 80 will move outwardly resulting in such rotation of the shafts 31 to cause the cams 33 to engage the ears or extensions 29 of the brake or band sections comprised in each of the clamping units to cause said band or brake 85 sections to have the requisite frictional contact with the periphery of the housing or casing H whereby said casing or housing H may be caused to rotate in unison with the shafts D and S so that the speed of the 90 driven shaft S will be increased. It will be understood that when the clamping action of the clutching units C is sufficient to hold the casing or housing H against rotation relative to said clutching units, the shaft 95 S will rotate in high, but the rotation of the shaft S between high and low will depend upon the amount of slip the housing or casing H may have with respect to the clutching units C. In accordance with the amount 100 of slip of the housing or casing H with respect to the clutching units C, the speed of the shaft S will be reduced above low. As before stated, the low speed of the shaft S occurs when the clutching units C are out of 105 frictional or working engagement with the housing or casing H.

Upon starting of the motor, the shaft D rotates and at which time the clutching units C are in neutral or release and as the shaft 110 D rotates, the shaft S is caused to rotate at a lower speed in the same direction through the operative connection afforded by the housing or casing H and the gear assembly carried thereby and coacting with the shafts 115 D and S as hereinbefore set forth. During this period, the clutching mechanism comprising the band or brake sections 9 coacting with the annular flange 10 hold the housing or casing A against movement reverse to 120 the direction of travel of the shaft S. As the speed of the motor increases dependent upon the load thereon, the shaft S will correspondingly increase in speed and as the disc or plate 24 rotates with said shaft S, the shafts 125 31 will be automatically rocked under the influence of the centrifugal force created by the weighted arms 34 to cause the brake or band sections 26 of the clutching units C to frictionally engage the periphery of the 130

housing or casing H whereby said housing or casing H is caused to rotate in unison with the shafts D and S and in the same direction. The greater the frictional contact 5 of the units C with the housing or casing H, the greater the rotating speed of the shaft S. In other words, when the clutching units C grip the casing or housing H in a manner to prevent rotation or slipping between said 10 housing or casing H and the clutching units C, the shafts D and S will rotate at the same speed but this maximum or high speed will be correspondingly decreased in accordance with the extent or amount of slip or inde- 15 pendent relative movement of the casing or housing H and the clutching units C, so that it is possible with my improved transmission to obtain automatically the different speeds between high and low and as may be re- 20 quired by the load of the engine.

The provision of a plurality of clutching units C in connection with a single or common rotatable element, constitutes an essential feature of my invention and par- 25 ticularly when each of the clutching units in itself is of a maximum tension or strength insufficient in itself to hold the housing or casing H against slipping or rotation relative to the clutching unit. However, by 30 providing a number of clutching units of an aggregate or total tension to hold the casing or housing H against such relative rotation or slip, it has been fully demonstrated in practice that undue heating of the clutching 35 units is eliminated and that the life thereof is materially prolonged because each of the separate elements is not subjected to the same amount of wear as would be the case if only a single clutching unit of requisite 40 tension or strength was employed.

It is also to be understood that the cams 33 are so arranged upon the shafts 31 to coact with the extensions or ears 29 in a manner to cause all of the clutching units C 45 to frictionally engage with the housing or casing H at substantially the same moment, although should there be any slight or minute variation in the applications of these separate elements, the efficiency of the series 50 of clutching units is not reduced.

It is to be understood that the band or brake sections 26 comprised in the clutching units C are normally maintained substantially out of frictional contact with the cas- 55 ing or housing H and, as herein disclosed, this is accomplished by the retractile mem- bers or springs x.

It is of the utmost importance to provide 60 means whereby each of the arms 34 is held against outward swinging movement under centrifugal force beyond a certain point and thus prevent the clutching elements C from engaging the housing H and thus prevent undue wear upon the brake sections 26 when 65 it is desired to run at any fixed speed for

any definite time as might be the case in running in several miles of mud or sand or long grades or other road conditions.

Coacting with each of the arms 34 is a stop member M overlying the outer face of 70 the disc or plate 24. The member M com- prises an elongated bar 36 disposed through the brackets 37 and provided at its opposite ends with the outstanding lugs 38 and 39, the lug 38 being positioned in relative close 75 proximity to the axial center of the disc or plate 24 while the second lug 39 is disposed in the path of travel of an arm 34. The elongated member 36, when free, moves out- 80 wardly with the arm 34 in order to permit the desired clutching actions through the medium of the elements C as hereinbefore referred to. The outer end portion of each of the elongated members 36 is provided with a lug 40 which slidably engages within 85 a slot 41 properly positioned in the disc or plate 24.

The outer end or head 1 of the casing A is provided with a bearing 2 through which extends the shaft S. The bearing 2 within 90 the casing A closely approaches the hub of the disc or plate 24. Surrounding the inner portion of the bearing 2 or that portion within the casing A is a collar or sleeve 42 provided in its periphery with an annular 95 groove or channel 43 and in which is adapt- ed to be engaged a yoke or the like extend- 100 ing exteriorly of the casing A to provide manual means whereby the collar or sleeve 42 may be moved or shifted longitudinally of the shaft S or toward or from the disc or plate 24 as may be required.

The collar or sleeve 42 is provided with an inwardly directed sleeve 44 having its in- 105 inner face or wall spaced from the bearing 2 so that when the collar 42 is moved in- wardly or in a direction toward the disc or plate 24, the sleeve 44 will pass over the lugs 38 of the members M whereby said members will be held against outward move- 110 ment so that the lugs 39 operate to limit the outward movement of the arms 34 to prevent the clutching elements C from en- gaging the housing H.

The free edge of the sleeve 44 is beveled 115 inwardly, as at 45, while the outer ends of the lugs 38 are correspondingly beveled, as at 46. The beveled faces 45 and 46 permit the sleeve 44, when the collar 42 is moved inwardly or toward the disc or plate 24, to 120 properly and effectually engage the lugs 38 to retract or move inwardly the members M from their extreme outward position, so that the clutching elements C may be ren- 125 dered inoperative and held in such condi- tion while the transmission mechanism is in operation and thus prevents the housing H from becoming a unit and to allow the drive for an indefinite time without wear or heat upon the clutching elements C and to allow 130

a fixed speed or ratio to be obtained which would be desirable when running in mud or other conditions where a positive low or intermediate speed is preferred. It is to be understood that this rendering of the clutching elements C is applicable to low or second or any number of intermediate speeds and it is, therefore, to be understood that the present invention is not limited to any particular speed.

From the foregoing description it is thought to be obvious that a power transmission mechanism constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In a transmission mechanism, a driving shaft, a driven shaft, means operatively connecting said shafts including a member constituting a drum, said member being loosely mounted on both of said shafts, a gear assembly carried by the member and coacting with said shafts, a clutching unit carried by one of the shafts and coacting with the drum, means operable under the influence of centrifugal force for adjusting the clutching element into frictional engagement with the drum, and means directly engaging said last named means for rendering the same inoperative.

2. In a transmission mechanism, a driving shaft, a driven shaft, means operatively connecting said shafts including a member constituting a drum, said member being loosely mounted on both of said shafts, a gear assembly carried by the member and coacting with said shafts, a clutching unit carried by one of the shafts and coacting with the drum, means operable under the influence of centrifugal force for adjusting the clutching element into frictional engagement with the drum, and manually operated means directly engaging said last named means for rendering the same inoperative.

3. In a transmission mechanism, a driving shaft, a driven shaft, means operatively connecting said shafts including a member constituting a drum, said member being loosely mounted on both of said shafts, a gear assembly carried by the member and coacting with said shafts, a clutching unit carried by one of the shafts and coacting with the drum, means operable under the influence of centrifugal force for adjusting

the clutching element into frictional engagement with the drum, said means including an arm moving outwardly under centrifugal force, means coacting with said arm for holding the same against such outward movement, said means including a member supported for sliding movement and provided with a lug with which the arm engages, and means engageable with said member for holding the same against outward movement.

4. In a transmission mechanism, a driving shaft, a driven shaft, means operatively connecting said shafts including a member constituting a drum, said member being loosely mounted on both of said shafts, a gear assembly carried by the member and coacting with said shafts, a clutching unit carried by one of the shafts and coacting with the drum, means operable under the influence of centrifugal force for adjusting the clutching element into frictional engagement with the drum, said means including an arm moving outwardly under centrifugal force, means coacting with said arm for holding the same against such outward movement, said means including a member supported for sliding movement and provided with a lug with which the arm engages, a second lug carried by the member, and a movable element overlying the second named lug when the element is in one position for holding the member against movement.

5. In a transmission mechanism, a driving shaft, a driven shaft, means operatively connecting said shafts including a member constituting a drum, said member being loosely mounted on both of said shafts, a gear assembly carried by the member and coacting with said shafts, a clutching unit carried by one of the shafts and coacting with the drum, means operable under the influence of centrifugal force for adjusting the clutching element into frictional engagement with the drum, said means including an arm moving outwardly under centrifugal force, means coacting with said arm for holding the same against such outward movement, said means including a member supported for sliding movement and provided with a lug with which the arm engages, a second lug carried by the member, and a movable element overlying the second named lug when the element is in one position for holding the member against movement, the coacting end portions of the element and second named lug being correspondingly beveled.

6. In combination with a centrifugally operated element including an arm swinging outwardly under centrifugal force, a member supported for sliding movement, said arm engaging the member whereby said member and arm are adapted to move outwardly in unison, and means for holding

the member against such movement, whereby the arm is rendered inactive.

7. In combination with a centrifugally operated element including an arm swinging outwardly under centrifugal force, a member supported for sliding movement, said arm engaging the member whereby said member and arm are adapted to move outwardly in unison, and means engageable for holding the member against such movement whereby the arm is rendered inactive, said means, when engaged with the member, holding said member at substantially the limit of its inward movement.
- 10 8. In combination with a centrifugally operated element including an arm swinging outwardly under centrifugal force, a member supported for sliding movement and provided with a lug with which the arm engages when swinging outwardly, a
- 15
- 20

second lug carried by the member, and a movable element engaging the second lug when the element is in one position for holding the member against movement.

9. In combination with a centrifugally operated element including an arm swinging outwardly under centrifugal force, a member supported for sliding movement and provided with a lug with which the arm engages when swinging outwardly, a second lug carried by the member, and a movable element engaging the second lug when the element is in one position for holding the member against movement, the coacting portion of the element and second named lug being correspondingly beveled.

In testimony whereof I hereunto affix my signature.

WILLIAM I. WHEELER.
